RESILIENT TARGET

Raymond L. Barker, Chicago, Ill.

Application October 5, 1945, Serial No. 620,423

9 Claims. (Cl. 273—102)

1

My invention contemplates and has for its primary object the provision of novel game apparatus which will receive a charge of energy from a ball or other suitable missile thrown against it and instantly release that energy to repel the missile along a line and at a speed influenced and largely determined by such varying and variable factors as (a) the spot on the impact face of the apparatus contacted by the missile, and (b) the traveling direction, (c) the velocity, and (d) the spin or english, if any, of the missile at the instant of its engagement with such impact face.

Another object of my invention is to provide such an apparatus that economically may be produced with manufacturing equipment and from a variety of materials, ordinarily readily available.

Still another object of my invention is to provide such an apparatus, in a light and portable form, that occupies a minimum of space when not in use.

Yet another object of the invention is to so construct such an apparatus that it will withstand, without perceivable or significant injury, an indefinitely enormous number of impacts by appropriately sized and shaped missiles tossed or hurled against it.

The aforesigned and other objects, features and advantages of my invention will appear from the following detailed description thereof, wherein reference is made to the accompanying sheet of drawings, wherein:

Fig. 1 is a side elevational view of an embodiment of my invention that suitably comprises a supporting frame of metal;

Fig. 2 is a front elevational view of the same;

Fig. 3 is a fragmentary sectional view that may be regarded as taken in the plane 3—3 of Fig. 2, and looking in the direction indicated by the arrows;

Fig. 4 is a fragmentary front elevational view of the upper left corner of the apparatus depicted in the preceding figures; and

Fig. 5 is a fragmentary sectional view, generally similar to Fig. 2, depicting an embodiment of my invention wherein the supporting frame suitably may be a composite of wood and metal.

Similar characters of reference refer to similar parts throughout the several views.

Referring to Figs. 1 to 4, it will be noted that my novel game apparatus comprises a suitably shaped framework 10 which, for purpose of illustration, has been depicted as rectangular, with rounded corners. Such framework may consist of two principal members, namely, a rear mem-

2

ber 11 that may be generally channel-shaped in cross section, with its flanges presented rearwardly, and a front member 12 that has flat surfaces disposed in opposition to the web portion of member 11. Members 11 and 12 desirably are beaded at 11a and 12a to provide them with aligned mutually facing channels which extend continuously around the framework 10.

The framework desirably is provided with downward extensions or legs 13 and with suitable appropriately articulated easel members 14, 15 and 16 arranged and adapted to lie closely adjacent to and in the plane of the framework when not in use.

15 A salient feature of the present invention is an impact face, generally indicated at 17, which resiliently will yield under the impact of a ball or other suitably sized and shaped missile tossed or hurled against it. It is desirable that such impact face be wholly or largely curvilinear convex, and I prefer that it resemble a surface of a spheroid.

I also prefer that the impact face 17 be an outer surface of an inflatable bag, preferably, but not necessarily, of single ply, that is disposed in and carried by framework 10 and has a continuous perimetrical or peripheral margin securely clamped between the members 11 and 12 of the framework. Accordingly, in the embodiment of my invention now being discussed, I provide an inflatable bag consisting of a front wall 18 and a rear wall 19. Such walls 18 and 19 are formed of pliable sheet or sheet-like material, stretchable sheet-like rubber of the kind frequently found in inflatable balls or the bladders thereof being preferred, and have marginal portions 20—20 clamped between and held in continuous face-to-face contact by the members 11 and 12 of the framework. When the inflatable bag is formed of sheet-like rubber, the front and rear walls 18 and 19 desirably have their perimetrical or peripheral portions integrally joined and curved around, and if desired vulcanized to a cylindrical core member 21 of the wire or rubber or other suitable compressible or non-compressible material. A plurality of screws 22 and their nuts and lock washers, or equivalent means, are relied upon to draw the members 11 and 12 toward each other securely to hold the perimetrical or peripheral portions of the bag walls in the framework 10, with the core 21 and the bag portions curving around it occupying the opposed generally semi-cylindrical channels afforded by the beads 11a and 12a.

While the bag may be inflated with any gas

in any preferred manner, and with the aid of various suitable instrumentalities, I find it convenient to inflate the bag by air pressure from the mouth, blown through the rubber inflating stem 23, which may be closed against the escape of air in any suitable way, one suitable way being to flatten the stem by drawing its free end under the adjacent loop 24, having its ends vulcanized or otherwise secured to the bag wall 19.

When the bag walls 18 and 19 are formed of stretchable sheet-like material, I prefer that the central portion of the front wall 18 be somewhat thicker than the back wall 19, so that the inflated bag will protrude more from the rear than from the front of the framework 10, and so that the impact face 17 may the longer withstand such wear as results from its repeated contacts with the balls or other missiles striking it.

Fig. 5 depicts a framework construction that has definite advantages when wood is to be utilized. Here the front member of the framework, indicated at 120, is formed of wood and has surfaces 120a and 120b disposed in planes at right angles to each other. The rear member in this instance, being indicated at 110, may be formed of metal or wood. It comprises the generally flat portion 110a having the flange 110b which has a rounded front edge 110c. Screws 220 fasten the members 110 and 120 together. In this form of the invention the contacting perimetrical or peripheral margins of the walls 18 and 19 of the inflatable bag are primarily clamped between member 120 and flange 110b and are secondarily clamped between member 120 and the portion 110a of the rear member 110.

It is preferred that balls be the missiles tossed or hurled against the impact face 17. Solid rubber balls are excellent for the purpose, but balls of other materials will suffice. Merely to state examples, and not by way of limitation, I will state that excellent results have been realized when the impact face 17 has an area of substantially five square feet for contact with missiles tossed or hurled against it, and when such missiles are solid soft rubber balls, having diameters of two inches or larger. The missiles are not necessarily round. They may be cubical or of irregular shape. When cubical their faces may bear arbitrary numbers or be consecutively numbered as are dice.

The game apparatus just described may be disposed on a beach, lawn, court, or indoor or outdoor floor.

An interesting solitaire pastime, affording beneficial exercise to the player, and requiring for best results accuracy and skills which the average player can develop only by practice, consists in standing in front of the apparatus and tossing or hurling against the impact face 17 balls or other appropriately sized and shaped missiles which are returned to the player either directly or via a bounce from the surface on which the player stands. Similarly interesting and beneficial skill-developing games for two or more players may involve each player so tossing or hurling a missile or missiles against the impact face, that such missile or missiles will be calculated to return to him, either directly or with a bounce, or go toward or avoid another player or players.

Generally speaking, the speed and direction of a ball repelled by the impact face 17 will be influenced by and largely be determined by such factors as the particular spot on the impact face contacted by the ball, and the direction in which the ball is moving, the velocity of the ball, and the

spin or english, if any, of the ball, at the instant the ball engages the impact face.

When, as is preferred, the impact face 17 is provided by a flexible stretchable member distended to curvedly convex contour by air or other gas pressure exerted upon it from behind, a spot on the impact face against which a ball strikes will yield rearwardly to the inertia of the ball and then instantly reverse the direction of the ball and repel it as the energy momentarily stored in the wall 18 and in the gas cushion is discharged. Whether the shape of the gas bag frame be approximately square or approximately circular, the distended forward portion of the impact face, against which the ball or balls should be aimed, will approximate a curvedly convex surface of a spheroid.

Having thus illustrated and described my invention, what I claim as new and desire to secure by Letters Patent of the United States is:

1. Game apparatus, capable of receiving a charge of energy from a missile thrown against it and substantially instantly releasing that energy to repel the missile with speed and in a direction influenced more or less by such varying and variable factors as the spot on the apparatus contacted by the missile, and the traveling direction of the missile, and the velocity of the missile, and the spin, if any, of the missile, at the instant the missile engages the apparatus, comprising a sheet of flexible stretchable material, a marginal frame for said sheet, means lying behind said sheet and cooperating therewith to form a compartment for fluid under pressure, which causes said sheet to present a curvedly convex impact face bounded by said frame; whereby engagement of said impact face by a missile causes but a momentary change in the shape of said fluid compartment while the sheet is held marginally substantially stationary by said frame.

2. Game apparatus as set forth in claim 1 wherein the sheet of flexible stretchable material is thicker centrally than it is marginally.

3. Game apparatus, capable of receiving a charge of energy from a missile thrown against it and substantially instantly releasing that energy to repel the missile with speed and in a direction influenced more or less by such varying and variable factors as the spot on the apparatus contacted by the missile, and the traveling direction of the missile, and the velocity of the missile, and the spin, if any, of the missile, at the instant the missile engages the apparatus, comprising a sheet of flexible material, a marginal frame for said sheet, a second flexible sheet lying behind and cooperating with the first sheet to form a compartment for fluid under pressure which causes said sheet to present a curvedly convex impact face bounded by said frame; whereby engagement of said impact face by a missile causes but a momentary change in the shape of said fluid compartment while the sheet is held marginally substantially stationary by said frame.

4. Game apparatus as set forth in claim 3 wherein the material of at least one of the specified sheets is stretchable as well as flexible.

5. Game apparatus as specified in claim 3 wherein the material of each of the specified sheets is stretchable as well as flexible.

6. Game apparatus as specified in claim 3 wherein the material of each of the specified sheets is stretchable as well as flexible with the material of the rear sheet being more easily stretchable than the material of the front sheet.

7. Game apparatus as specified in claim 3

wherein the two specified sheets are integrally marginally joined to constitute a fluid-tight bag.

8. Game apparatus, capable of receiving a charge of energy from a missile thrown against it and substantially instantly releasing that energy to repel the missile with speed and in a direction influenced more or less by such varying and variable factors as the spot on the apparatus contacted by the missile, and the traveling direction of the missile, and the velocity of the missile, and the spin, if any, of the missile, at the instant the missile engages the apparatus, comprising a resilient target member which presents a curvedly convex impact face, and a support for said resilient target member which permits said target member momentarily to change its shape, but prevents it from moving as a whole, under forces imparted to it by missiles hurled against such impact face, said impact face assuming its normal contour and position substantially instantly

5 after being engaged by a missile hurled against it.

9. Game apparatus as set forth in claim 8 wherein the target is a receptacle containing gas under pressure and having one flexible wall which bulges in concavo-convex cross section to afford the specified curvedly convex impact face.
